To all whom it may concern:

Be it known that I, George D. Atwood, citizen of the United States, residing at Brooklyn, county of Kings, State of New York, have invented a new, original, and ornamental Design for a Box, of which the following is a specification, reference being had to the accompanying drawing, forming a part thereof, in which—

Figure 1 is a plan view of a box showing my new design, and

Figure 2 is a side elevation.

I claim:

The ornamental design for a box, substantially as shown.

GEO. D. ATWOOD.
